UNITED STATES PATENT OFFICE

2,483,365

COMPARTMENT LOCK

Henry J. Feldmann, Detroit, Mich., assignor to
 The Yale & Towne Manufacturing Company,
 Stamford, Conn., a corporation of Connecticut

Application July 2, 1946, Serial No. 681,086

17 Claims. (Cl. 70—83)

1

This application relates to a lock of the type utilized for locking compartments, boxes, chests, and other similar structures. More particularly, my invention relates to a lock of the type in which a tumbler controlled push piece is adapted to retract a locking bolt when the tumblers are properly positioned.

In locks of the particular class, it has been customary to prevent inward movement of the tumbler controlled push piece except when the said push piece is in a particular rotated position, there being utilized for the purpose an obstruction on the lock body in alignment with a part of the push piece in one position thereof. As a feature of my invention, I utilize each of the tumblers contained in my push piece for preventing movement thereof until the tumblers are retracted or are rotated with the push piece into alignment with a releasing slot of the lock body in which the push piece is mounted. This phase of the invention is an improvement over that described and claimed by Charles Ledin in Patent No. 2,399,812 dated May 7, 1946.

As a further feature of my invention, the locking bolt is adapted for assembly in the lock through a particular shaping of the lock body. As a further feature of this part of the invention, the locking bolt is retained in position through its inherent relationship to the lock body.

As a feature also of my invention, the locking stress against the bolt of my lock is accepted in a novel manner by the lock body while the release movement of the bolt is accomplished through a withdrawal thereof from its strike with a minimum of friction.

More particularly, it is a feature of my invention that the locking bolt is adapted for sliding and pivotal movement, the push piece being adapted to impart sliding movement to the locking bolt which then pivots automatically out of locking position. As a further feature of this part of the invention, spring means are utilized to maintain the locking bolt in a particular position and to resist both its pivotal and sliding movement. As a particularly important feature of the invention, the spring means is preferably a single torsion spring mounted in a novel and unusual manner relatively to the locking bolt.

A still further feature of my invention resides in the utilization of means for covering the tumbler slots of the lock body. More particularly, this feature of the invention embodies the utiliza-

2

tion of a lock body retainer that holds covering means for the slots in covering position.

A still further feature of the invention resides in the utilization of a retainer for the lock body adapted for application to the lock body without tools or particular holding means, and functioning to maintain the lock body pressed into its preferred mounted position.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto.

Referring now to the drawings, Fig. 1 is a vertical section through the lock of my invention showing it applied to a compartment door and in locking relation to the housing to which the door is fitted. Fig. 2 is a section taken along lines 2—2 of Fig. 1, while Fig. 3 is a section taken along lines 3—3 of Fig. 1. Fig. 4 is a view of the parts of Fig. 3 showing the tumbler controlled push piece rotated 180° and the key in tumbler controlling position. Fig. 5 is a front view broken away partially to show the action of a retaining tumbler that functions to hold the tumbler controlled push piece within the lock body. Fig. 6 is an end view and partial section taken along lines 6—6 of Fig. 1. Fig. 7 shows the parts of Fig. 1 with the lock bolt retracted. Fig. 8 is an elevation of the lock body of my invention showing the individual locking slots in which the tumblers lie when the tumbler controlled push piece is in locked position. Fig. 9 is a view similar to Fig. 8, illustrating the lock body retainer and the manner in which it covers the tumbler locking slots. Fig. 10 is a perspective view of the lock body retainer.

Referring now more particularly to the drawings, the lock body of my invention is designated by reference numeral 10 and has mounted for rotation and sliding movement therein a tumbler controlled push piece 11 that is really a key plug formed with a keyway 12 and slots for a series of locking tumblers 13. The push piece or key plug 11 is equipped with a retaining and limiting lug 14 best illustrated in Figs. 2 and 5 adapted to lie behind a scallop S applied to the lock body and moving in a slot 14a of said lock body. It is the function of this lug 14 to prevent removal of the key plug or push piece 11 from the lock body 10, while

limiting the plug rotation to 180°, all as those skilled in the art will fully understand.

When the key plug 11 is in its rotated position of Fig. 3, its several tumblers 13 will be spring projected by a series of springs 16 into a series of individual locking slots 17 of the lock body 10. These slots 17 are probably best shown in Figs. 2, 3, and 8, and preferably there will be one tumbler 13 in each slot, although it is conceivable that it may be desirable at times to make the slots longer so that a plurality of tumblers may be positioned in each slot. Those skilled in the art will understand that each tumbler in each slot 17 will prevent endwise movement of the key plug or push piece 11 from its position of Figs. 1 and 2 to its position of Fig. 7. If a key K is inserted into the keyway 12 as shown in Fig. 2, the tumblers 13 will be retracted from the locking slots 17, and will move into a position with their peripheries in alignment with the periphery of the key plug or push piece 11. It is obvious that it will then be possible to move the key plug 11 inwardly from its position of Fig. 1 for a purpose to appear presently.

With the tumblers retracted by the key as just described, it is possible also to rotate the key plug or push piece 11 to its position of Fig. 4. If the key K be then withdrawn, the tumblers will be projected by the several springs 16 into a long narrow control slot 18 positioned 180° from the individual locking slots 17. As best seen in Fig. 2, the slot 18 extends to a considerable length in the lock body beyond the individual slots 17 and terminates in an end wall 19. It is obvious, of course, that with the several tumblers 13 in the slot 18, it is possible to push the key plug or push piece 11 until the innermost tumbler 13 strikes the end wall 19. This will not ordinarily occur as the key plug need never move inwardly beyond its position of Fig. 7.

The inward movement of the key plug or push piece 11 is utilized to actuate a locking bolt 20. This locking bolt 20 is adapted for co-action with a strike 21 carried by a compartment surface 22, and when in the position of Fig. 1 it maintains in closed position a door 23 on which the lock body 10 is mounted.

The locking bolt 20 is preferably carried on a pin or shaft 24, and, as a matter of fact, the bolt 20 may be integral with the shaft 24 so that the shaft will form trunnions for the bolt. The particular method of fabricating the bolt and the other parts of my invention is, of course, not important as methods of fabrication change from time to time as manufacturing techniques improve. For mounting the bolt 20, the lock body 10 is formed with a slot 25 extending downwardly toward the bore 26 of the lock body 10 in which the key plug or push piece 11 rotates and moves endwise. The lock body is further equipped with opposed slots 26a best seen in Figs. 1, 2, and 6 that extend longitudinally of the lock body and terminate at the extreme rear end thereof. In order to apply the locking bolt 20 to the lock body 10, it is merely necessary to insert the bolt through the open rear end of the lock body with the shaft 24 sliding in the opposed slots 26a. Naturally, the key plug or push piece 11 will not at the particular time be within the lock body 10. As soon as the locking portion 20a of the bolt 20 is inserted opposite the slot 25, it will be free to rotate on shaft 24 into its position of Fig. 1.

A single torsion spring 27 that is wound as best illustrated in Fig. 6, is adapted for maintaining

the locking bolt 20 in its position of Fig. 1. In effect, this single spring 27 may be considered as comprising two springs with each of the said two springs having a dual function. Thus, glancing at Fig. 6, each of the two springs may be considered as having one leg at 27a pressing against the lock body and a second leg 27b pressing against the locking bolt 20. The spring action will naturally tend to move the shaft or pin 24 to the right in Fig. 1, carrying the bolt portion 20b against the end surface 11a of the key plug or push piece 11. Simultaneously, the bolt 20 will be spring rotated counterclockwise about the axis of the shaft 24 in its locking position. When the key plug or push piece 11 is moved to the left in Fig. 1 its surface 11a will press against the surface 29b of the locking bolt 20 to move it toward the left to its position of Fig. 7. As the bolt so moves, a camming surface 28 on the lock body will co-act with the camming surface 20c of the locking bolt 20 to cam the bolt into the slot 25 as best shown in Fig. 7. This action will, of course, release the door 23 so that it may be moved to open position.

It is important to consider at this point that the locking thrust against bolt 20 is accepted by the lock body at 28, rather than by pivot shaft 24. This contributes a very secure and solid locking action while allowing a smooth endwise withdrawal of the bolt by the key plug or push piece 11 accompanied by a releasing rotation of the bolt free of friction from its cooperating strike 21.

The individual locking slots 17 are adapted to be covered by one of the two ears 29 of a lock body retainer 30 so as to prevent the entrance of dirt into the lock body as is probably best appreciated from Fig. 9. The ears 29 have a second function, being utilized to lie against detent surfaces 31 of the lock body 10 so as to retain the lock body from movement outwardly relatively to a hole 32 of the door 23 on which it is mounted. In applying the lock body to the door, the retainer 30 will be placed against the rear surface of the said door and the lock body then inserted. The retainer 30 is made of spring-like material and the ears 29 are therefore adapted to flex into and out of retaining position. Thus, the said ears 29 will first be moved outwardly by the lock body and then will spring inwardly toward the detent surfaces 31 as seen in Fig. 2. This position of the ears will be assumed just as the scalped head 33 of the lock body 10 is applied against the outer surface of the door 23, and it will be the function of the spring-like retainer 30 and the ears 29 to force the scalped head 33 of the lock body yielding against the door 23. This prevents rattling of the lock body relative to the door, and maintains it in effective operating position. It is obvious, also, that the locking bolt 20 will be maintained firmly against the lock body and the push piece 11 for effective operation.

I believe that the construction of my invention and its function will now be apparent to those skilled in the art.

I now claim:

1. In a lock of the class described, a lock body having a bore, a key plug slidable in said bore, said body having a pair of opposed slots, a pin slidable in said slots transversely of said bore, a bolt carried by said pin and slidably therewith, said lock body having a third slot transverse of said first slots and communicating with said

bore and through which said bolt extends from said pin, and a surface on said key plug adapted to impinge against said bolt to push it and its pin rearwardly relatively to said lock body.

2. In a lock of the class described, a lock body having a bore, a key plug slidable in said bore, said body having a pair of opposed slots, a pin slidable in said slots transversely of said bore, a bolt carried by said pin and slidable therewith, said lock body having a third slot transverse of said first slots and communicating with said bore and through which said bolt extends from said pin, a surface on said key plug adapted to impinge against said bolt to push it and its pin rearwardly relatively to said lock body, and a surface of said lock body adapted to cam said bolt downwardly into said third slot as said bolt and pin move rearwardly of said lock body.

3. In a lock of the class described, a lock body having a bore, a key plug slidable in said bore, said body having a pair of opposed slots, a pin slidable in said slots transversely of said bore, a bolt carried by said pin and slidable therewith, said lock body having a third slot transverse of said first slots and communicating with said bore and through which said bolt extends from said pin, a surface on said key plug adapted to impinge against said bolt to push it and its pin rearwardly relatively to said lock body, and spring means pushing said pin and bolt bodily against the said surface of said key plug while rotating said bolt outwardly of said third slot in a locking direction.

4. In a lock of the class described, a lock body having a bore, a key plug slidable in said bore, said body having a pair of opposed slots, a pin slidable in said slots transversely of said bore, a bolt carried by said pin and slidable therewith, said lock body having a third slot transverse of said first slots and communicating with said bore and through which said bolt extends from said pin, a surface on said key plug adapted to impinge against said bolt to push it and its pin rearwardly relatively to said lock body, a surface of said lock body adapted to cam said bolt downwardly into said third slot as said bolt and pin move rearwardly of said lock body, and spring means pushing said pin and bolt bodily against the said surface of said key plug while rotating said bolt outwardly of said third slot in a locking direction.

5. In a lock of the class described, a lock body having a bore, a key plug slidable in said bore, said body having a pair of opposed slots, a pin slidable in said slots transversely of said bore, a bolt carried by said pin and slidable therewith, said lock body having a third slot transverse of said first slots and communicating with said bore and through which said bolt extends from said pin, a surface on said key plug adapted to impinge against said bolt to push it and its pin rearwardly relatively to said lock body, and a single spring pushing said pin and bolt bodily against the said surface of said key plug while rotating said bolt outwardly of said third slot in a locking direction.

6. In a lock of the class described, a lock body having a bore, a key plug slidable in said bore, said body having a pair of opposed slots, a pin slidable in said slots transversely of said bore, a bolt carried by said pin and slidable therewith, said lock body having a third slot transverse of said first slots and communicating with said bore and through which said bore extends from said pin, a surface on said key plug adapted to impinge against said bolt to push it and its pin rearwardly

relatively to said lock body, a surface of said lock body adapted to cam said bolt downwardly into said third slot as said bolt and pin move rearwardly of said lock body, and a torsion spring about said pin having one end pressing against a surface of said lock body to press said bolt and pin bodily toward said key plug, the other end of said spring pressing against said bolt to rotate said bolt in the axis of said pin outwardly of said third slot.

7. In a lock of the class described, a lock body having a bore, a key plug slidable in the forward end of said bore, said body having a pair of opposed slots extending from the rear end of said lock body toward the front end thereof and the said key plug, a pin slidable in said slots transversely of said bore, a bolt carried by said pin and slidable therewith, said lock body having a third slot transverse of said first slots and communicating with said bore and through which said bolt extends from said pin, and a surface on said key plug adapted to impinge against said bolt to push it and its pin rearwardly relatively to said lock body.

8. In a lock of the class described, a lock body having a bore, a key plug slidable in the forward end of said bore, said body having a pair of opposed slots extending from the rear end of said lock body toward the front end thereof and the said key plug, a pin slidable in said slots transversely of said bore, a bolt carried by said pin and slidable therewith, said lock body having a third slot transverse of said first slots and communicating with said bore and through which said bolt extends from said pin, a surface on said key plug adapted to impinge against said bolt to push it and its pin rearwardly relatively to said lock body, a torsion spring about said pin having one end pressing against a surface of said lock body to press said bolt and pin bodily toward said key plug, the other end of said spring pressing against said bolt to rotate said bolt in the axis of said pin outwardly of said third slot.

9. In a lock of the class described, a lock body, a key plug slidable in a bore of said lock body, said lock body having a slot leading to said bore, a bolt adapted to move into and out of said slot, means mounting said bolt for sliding movement relatively to said lock body, said key plug having a surface for sliding said bolt relatively to said lock body, and a surface of said lock body adapted to cam said bolt into said slot as said bolt is moved by said key plug.

10. In a lock of the class described, a lock body, a key plug slidable in a bore of said lock body, said lock body having a slot leading to said bore, a bolt adapted to move into and out of said slot, means mounting said bolt for sliding movement relatively to said lock body, said lock body having a slot leading to said bore, a bolt adapted to lie in said slot and to extend outwardly thereof into locking position, trunnions mounting said bolt for pivotal and sliding movement relatively to said slot and lock body, a surface on said key plug adapted to impinge against said bolt to push it and its trunnion rearwardly relatively to said lock body, a torsion spring about said trunnion having one end pressing against a surface of said lock body to press said bolt and trunnion bodily toward said key plug, the other end of said spring pressing against said bolt to rotate said bolt in the axis of said trunnion outwardly of said slot.

11. In a lock of the class described, a lock body, a key plug slidable in a bore of said lock body, said lock body having a slot leading to said bore,

a bolt adapted to move into and out of said slot, means mounting said bolt for sliding movement relatively to said lock body, said lock body having a slot leading to said bore, a bolt adapted to lie in said slot and to extend outwardly thereof into locking position, trunnions mounting said bolt for pivotal and sliding movement relatively to said slot and lock body, a surface on said key plug adapted to impinge against said bolt to push it and its trunnion rearwardly relatively to said lock body, a torsion spring about said trunnion having one end pressing against a surface of said lock body to press said bolt and trunnion bodily toward said key plug, the other end of said spring pressing against said bolt to rotate said bolt in the axis of said trunnion outwardly of said slot, and a surface of said lock body adapted to cam said bolt into said slot as said bolt is moved by said key plug.

12. In a lock of the class described, a lock body, a key plug slidable in a bore of said lock body, said lock body having a slot leading to said bore, a bolt adapted to move into and out of said slot, means mounting said bolt for sliding movement relatively to said lock body and for said movement into and out of said slot, spring means urging said bolt out of said slot and lock body toward a locking position and simultaneously urging said bolt on said mounting means against the key plug, said key plug having a surface adapted to slide said bolt on its mounting means against the force of said spring, and a surface of said lock body adapted to cam said bolt into said slot as said bolt is moved by said key plug.

13. In a lock of the class described, a lock body, a key plug slidable in a bore of said lock body, said lock body having a slot leading to said bore, a bolt having a locking end adapted to move into and out of said slot, means mounting said bolt for sliding movement relatively to said lock body and for pivotal movement of said locking end into and out of said slot, said key plug having a surface for sliding said bolt relatively to said lock body, and a surface of said lock body adapted to cam said bolt on said mounting means into said slot as said bolt is moved by said key plug, said surface deadlocking said bolt against sliding movement when end pressure is applied directly to the locking end of said bolt.

14. In a lock of the class described, a lock body having a bore, a key plug slidable in said bore, said body having a pair of opposed slots, a pin slidable in said slots transversely of said bore, a bolt having a locking end carried by said pin and slidable therewith, said lock body having a third slot transverse of said first slots and communicating with said bore and through which the locking end of said bolt extends from said pin, a surface on said key plug adapted to impinge against said bolt to push it and its pin rearwardly relatively to said lock body, a surface of said lock body adapted to cam the locking end of said bolt downwardly into said third slot as said bolt and pin move rearwardly of said lock body, spring means pressing said bolt and pin bodily toward said key plug, while rotating the locking end of said bolt in the axis of said pin outwardly of said third slot, the position of said bolt when rotated outwardly of said third slot being such that end pressure against its locking

end is ineffective to move it rearwardly with said pin.

15. In a lock of the class described, a lock body, a key plug slidable in a bore of said lock body, said lock body having a slot leading to said bore, a bolt adapted to move into and out of said slot, means mounting said bolt for sliding movement relatively to said lock body and for said movement into end of said slot, spring means urging said bolt out of said slot and lock body toward a locking position and simultaneously urging said bolt on said mounting means against the key plug, said key plug having a surface adapted to slide said bolt on its mounting means against the force of said spring, and a surface of said lock body adapted to cam said bolt into said slot as said bolt is moved by said key plug and adapted to block rearward movement of said bolt when end pressure is applied to that part thereof outside said slot.

16. In a lock of the class described, a lock body having a bore, a key plug slidable in said bore, a bolt having a locking end, means mounting said bolt for sliding and pivotal movement in said lock body, a surface on said key plug adapted to impinge against a portion of said bolt spaced from said locking end to push it rearwardly relatively to said lock body on said mounting means, spring means pushing said bolt bodily against the said surface of said key plug while rotating said bolt relatively to said lock body in a locking direction, a surface of said lock body adapted to cam the locking end of said bolt in a direction opposed to that in which it is urged by the pressure of said spring when said bolt is moved inwardly by said key plug, and said surface deadlocking said bolt against sliding movement when end pressure is applied directly to the locking end of said bolt.

17. In a lock of the class described, a lock body, a key plug slidable in said bore, a bolt having a locking end, means mounting said bolt for sliding and pivotal movement on said lock body, a surface on said key plug adapted to impinge against a portion of said bolt spaced from said locking end to push it rearwardly relatively to said lock body on said mounting means, spring means pushing said bolt bodily against the said surface of said key plug while rotating said bolt relatively to said lock body in a locking direction, and surfaces on said lock body and bolt adapted to cam said bolt in a direction opposed by said spring when said bolt is moved inwardly on its mounting means by said key plug, while deadlocking said bolt against endwise movement when said pressure is applied directly to the locking end of said locking bolt.
